UNITED STATES PATENT OFFICE.

JOSEPH T. ROBERTS, OF ROSE HILL, ILLINOIS.

HOG-SCALDER AND FEED-COOKER.

No. 887,964.

Specification of Letters Patent.

Patented May 19, 1908.

Application filed January 15, 1907. Serial No. 352,431.

To all whom it may concern:

Be it known that I, JOSEPH T. ROBERTS, a citizen of the United States, residing at Rose Hill, in the county of Jasper and State of Illinois, have invented a new and useful Hog-Scalder and Feed-Cooker, of which the following is a specification.

This invention relates to apparatus for scalding hogs and for cooking stock food, and 10 has for its object to improve the construction and increase the efficiency and utility of devices of this character.

With this and other objects in view, which 15 will appear as the nature of the invention is better understood, the same consists in certain novel features of construction as herein-after fully described and claimed.

In the accompanying drawings, forming a 20 part of this specification, and in which corresponding parts are denoted by like designating characters, is illustrated the preferred form of embodiment of the invention capable of carrying the same into practical operation.

25 In the drawings thus employed:—Figure 1 is a perspective view of the improved apparatus. Fig. 2 is a longitudinal sectional elevation. Fig. 3 is a transverse section on the line 3—3 of Fig. 2.

30 In the improved device is comprised a furnace 10 of suitable construction and having a receptacle 11 for the hot water for the scalding operations, or in which the stock food is to be cooked.

35 The furnace portion of the apparatus may be of any desired form or of any required material, but for the purpose of illustration is shown with a sheet or plate metal shell having a grate 12, fire door 13, draft or ash 40 pit door 14 and smoke stack 15.

The receptacle 11 is formed with a flange 16 bearing upon the upper face of the shell, so that the receptacle may be readily removed when required.

45 Mounted for rotation as by bearings 17—18 upon the shell of the furnace adjacent to the receptacle 11, is a roller 19 having an operating lever handle 20 at one end and provided with spaced chains 21 extending transversely 50 of the receptacle 11 and detachably coupled by the end links to pins 22 at the opposite side of the receptacle. By this arrangement when the lever arm 20 is moved into its outward position as in Fig. 1, the chains will be 55 stretched tightly across the receptacle, and when the lever arm is moved into its inward

position, the chains will be “slacked” up and permitted to fall into the receptacle, as in Fig. 3. Thus the carcass of the hog may be lowered into the receptacle or raised there- 60 from as required, as hereafter described.

A rod 23 is pivoted at 24 by one end to the shell of the furnace and terminating in a hook 25 at the other end for bearing over the arm 20 when depressed to lock the same in that 65 position.

Mounted to swing from the shell of the furnace by hooks 26 and eye bolts 27 is a grating frame 28, the frame being supported in elevated position as in Fig. 1 by jointed brace bars 70 29, and connected respectively at their opposite ends to the furnace shell and to the grating. By this means the grating is firmly supported in elevated position, as in Fig. 1, or foldable alongside the shell, as in Fig. 3. 75 A similar grating frame 30 is hinged by one edge as at 31 to swing from the opposite side of the furnace and provided with braces 32 swinging at one end from the grating and adapted to bear by their free ends upon a 80 cleat 33 upon the furnace shell when the grating is elevated.

The operation of the apparatus is as follows:—The arm 20 is first depressed and the locking rod 23 applied, to hold the chains 21 85 stretched tightly across the receptacle 11, and the slaughtered hog rolled against the grating frame 30 when in depressed position and elevated thereby and rolled over upon the chains 21. The chains are then released 90 by rotating the roller 19 with the effect of submerging the carcass into the hot water, and again elevate it by reversing the motion of the arm 20 and again locking it by the rod 23 leaving the carcass upon the chains from 95 which it can be rolled upon the grating frame 28. The bristles are then detached and the carcass removed.

When the device is to be employed as a stock food cooker, the chains are detached 100 from the pins 22 and the grating frames detached or lowered, as may be preferred.

The apparatus is simple in construction, can be inexpensively manufactured, and will 105 be found very useful and convenient for the purposes described.

Having thus described the invention, what is claimed is:—

In a hog scalder and feed cooker, a hollow 110 sided furnace shell having a fuel door at one end and an escape flue near the opposite end, said shell having a top opening of less width

than the width of the shell, a scalding receptacle detachably hung within the opening and having laterally extended side and end flanges resting on the upper wall of the shell,
5 a plurality of chain supporting pins carried by the shell at points beyond one of the side flanges, a roller journaled in bearings carried by the shell at points beyond the opposite side flange, chains extending from the rollers
10 to the pins and detachable from the latter, an operating handle secured to one end of the roller, means suitably mounted upon the

shell for engaging and locking said handle to hold the chains in elevated position, and an adjustable grating frame pivoted to the 15 opposite sides of the shell.

In testimony that I claim the foregoing as my own, I have hereto affixed my signature in the presence of two witnesses.

JOSEPH T. ROBERTS.
